DESIGN FOR A CAP FOR COLLAPSIBLE TUBES

Rudolph S. Schenk, East Orange, N. J., assignor
to The Sun Tube Corporation, Hillside, N. J.,
a corporation of New Jersey

Application March 30, 1936, Serial No. 61,863

Term of patent 14 years

To all whom it may concern:

Be it known that I, Rudolph S. Schenk, a citizen of the United States, residing at East Orange, in the county of Essex and State of New Jersey, have invented a new, original, and ornamental Design for a Cap for Collapsible Tubes, of which the following is a specification, reference being had to the accompanying drawing, forming a part hereof.

Figure 1 is an elevational view of a cap for collapsible tubes showing my new design;

Figure 2 is a top plan view of the cap, and
Figure 3 is a bottom plan view of the cap.

I claim:

The ornamental design for a cap for collapsible tubes as shown.

RUDOLPH S. SCHENK.
